UNITED STATES PATENT OFFICE.

WALTER J. SCOTT, OF WOONSOCKET, RHODE ISLAND.

STOP MOTION FOR DRAWING FRAMES.

Application filed January 5, 1929. Serial No. 330,649.

This invention relates to an electric stop motion for drawing frames and is an improvement on my Patent No. 1,701,127, dated Feb. 5, 1929; and the object of the invention is to provide a stop motion of this character having an electric circuit closer unit which is located intermediate the sliver supply packages and the draft rolls, whereby the circuit is affected by the falling of a broken down sliver end upon the circuit-closing member to stop the machine.

A further object of the invention is the provision of an elongated flexible contact member set below the running slivers to extend across their line of travel, whereby the weight of any one of a number of such slivers upon breaking will fall upon this flexible finger and move the same to complete the circuit and energize a magnet to shift the belt or otherwise stop the machine.

With these and other objects in view, the invention consists of certain novel features of construction, as will be more fully described, and particularly pointed out in the appended claims.

In the accompanying drawings:

Fig. 1 is a side elevation showing the general arrangement of portions of the usual mechanism of a drawing frame with my improved contact member applied thereto and indicating one of the slivers in dotted lines as lying upon the contact finger the weight of which will move the same to stop the machine.

Fig. 2 is a detail showing a side elevation of the guide plate with my improved contact arm as connected to the frame of the machine adjacent this guide plate.

Fig. 3 is a perspective view of the circuit-closing unit which comprises a plate member with a contact arm mounted thereon.

Fig. 4 is a section showing my improved circuit closing unit as mounted on the frame of the machine and secured in position by one of the frame bolts.

Fig. 5 is a section on line 5—5 of Fig. 4 thru the bolt where one end of the contact finger is fixed and is insulated from its plate.

Fig. 6 is a section on line 6—6 of Fig. 4 showing the carbon contact as set in a lead collar in the contact carrying plate.

Fig. 7 is a view illustrating the sliver guide plate as located on an angle adjacent one of the sets of draft rolls and showing one of the slivers as having broken away and lying against the contact finger and bending

the same inward to make a contact and complete the circuit to stop the machine.

Fig. 8 is a view illustrating the belt shift lever as retained in operative position against tension of the belt shifting spring to be released by energizing the solenoid magnet when the electric circuit is closed.

Fig. 9 is a diagrammatic view illustrating the wiring diagram in which the contact finger is arranged to close the circuit by the weight of a broken sliver for operating the belt-shifting lever.

It is found in the practical operation of drawing frames of this character that where slivers are led from a plurality of supply packages thru a guide plate to be acted upon by a set of drawing rolls quite often one or more of these slivers are broken at a point intermediate the package and the guide plate and when this occurs the remaining slivers which continue to run naturally form a thin place in the yarn and this defective condition may continue for some time before being discovered by the operator and to obviate this difficulty, I have provided an automatically operable stop motion and have mounted its circuit closer intermediate the supply packages and the drawing rolls so that when any one of a set or group of slivers breaks at any point intermediate the supply package and these rolls, the falling of the broken end serves to effect the electric circuit to stop the machine.

My improved circuit closer is formed in a single unit which may be constructed complete and independent of the machine and is adapted to be readily attached thereto preferably by using one or more of the bolts already in the machine.

This circuit closing member is provided with an elongated contact arm which is set to extend across the line of travel of the sliver and below the same, whereby the weight of a falling broken sliver will move this flexible finger to complete the circuit and stop the machine; and the following is a detailed description of the present embodiment of my invention and showing one means by which these advantageous results may be accomplished:

With reference to the drawing, 10 designates a plurality of supply packages which may be sliver wound on spools, bobbins or the like on which the slivers 11 are wound and from which the slivers are led thru the slots 12 in the guide plate 13 thence over and

around the back draft rolls 14 thru the carrier rolls 15 and the front rolls 16 and after being drawn out or drafted the yarn is fed thru the flyer 17 to be wound upon the spool 5 or bobbin 18 which is raised and lowered on its spindle 21^a thru action of the rack 19 and pinion 20, which spindle and spool is rapidly rotated by the whirl 21 thru the belt 22 and pulley 23.

10 It is found in practice that the sliver ends often break down at some point between the supply package 10 and the guide plate 13 and that when this occurs and the remaining slivers continue to run without breaking down, 15 and without the broken sliver, a thin place in the yarn is formed and when later discovered necessitates cutting out and loss of the thin portion, and piecing up the broken ends and starting over again with the required 20 number of ends.

To obviate this difficulty, I have provided 25 automatic means in the form of an electric stop motion which I attach to the machine the same including a circuit closing unit 30 which comprises a plate 24 of suitable length slotted as at 25, thru which the securing bolt 26, which holds the guide plate 13 in position, may extend to bind this circuit closing plate in position or any other means of fastening may be employed.

One end of this plate is offset as at 26 or 35 raised above the plane of the body portion of the plate to provide a fixed support for the end 27 of the flexible contact finger 28, this end 27 being insulated from the plate by the insulation washers 29 and is bound against the end of the circuit wire 30 by means of the binding screw 31.

At the opposite end of this contact plate, 40 I have drilled a hole at 32 into which is set a lead collar 33 and in this lead collar is set a carbon contact button 34 against which the contacting end 35 of this flexible finger 28 is forced to complete the circuit thru the frame 36 back to the second circuit wire 37 which 45 is secured to this frame by a screw 38, by which construction it will be seen that this circuit-closing unit may be readily attached in position on the frame by the use of but a single bolt and that one being preferably one 50 that is already used in the machine.

By employing a carbon plug thru which to 55 make the circuit, sparking is obviated and by setting it in lead the liability of cracking is minimized.

As above described, this flexible bendable finger is supported in the plate 24 and insulated therefrom as shown in Fig. 5, and is connected to the circuit thru the wire 30, the 60 other wire of the circuit 37 being connected to the bar 26. The sliver guide plate 13 is set at an incline to a horizontal base line, as best illustrated in Fig. 1, whereby when any 65 one of these slivers breaks down the broken end falls and rests upon this very thin flexible

finger 28 which extends across the path of the running slivers, whereby the weight of the sliver causes this finger to spring inwardly into contact with the carbon plug 34, thus completing the circuit to energize the electro 70 magnet 38, trip the latch 39 and release the lever 40 which thru the action of spring 41 throws the rod 42 and shifts the belt from the tight pulley 43 to the loose pulley 44 thus stopping the machine. The electric circuit is 75 herein shown as being normally open but to so arrange the finger 28 that its movement will open the circuit instead of closing it, will fall within the spirit and scope of this invention.

80 My improved stop motion for drawing frames is extremely simple and practical in its construction and operation and by its use much time is saved and waste of good textile material is prevented, as the moment a 85 sliver is broken the machine is stopped which immediately gives notice to the operator who pieces up the ends and after the trouble is corrected the machine is started again.

The foregoing description is directed solely 90 towards the construction illustrated, but I desire it to be understood that I reserve the privilege of resorting to all the mechanical changes to which the device is susceptible, the invention being defined and limited only 95 by the terms of the appended claims.

I claim:

1. In an electric stop motion for drawing frames, an electric circuit, a stop motion in 100 said circuit, a set of sliver supply packages, draft rolls, a circuit closing unit comprising a body member, means for connecting said member to the machine intermediate the supply package and draft rolls, a flexible contact finger carried by said body member and 105 arranged to be actuated by the weight of any one of a plurality of broken slivers to affect the circuit and stop the machine.

2. In an electric stop motion for drawing frames, an electric circuit, a stop motion in 110 said circuit, sliver supply packages, draft rolls, a circuit closing unit comprising a body member adapted to be readily attached to the drawing frame at a point intermediate the supply packages and draft rolls, said 115 body member carrying an elongated flexible contact finger extending across the line of travel of the slivers to be moved by the weight of any one of a plurality of broken slivers to close the circuit and stop the machine.

3. In an electric stop motion for drawing frames, said frames having sliver supply packages and draft rolls, an electric circuit, a stop motion in the circuit including a circuit closing unit located intermediate said 125 supply packages and draft rolls, said unit comprising a body member connected to said frame and carrying a yieldable contact finger disposed below at substantially a right angle 130 to the line of travel of said sliver whereby a

broken sliver falling upon the finger moves it to close the circuit and stop the machine.

4. In an electric stop motion for drawing frames having sliver supply packages, draft rolls and a sliver guide plate intermediate said supply packages and draft rolls, an electric circuit, a stop motion in said circuit including a circuit closing unit located intermediate said supply packages and said draft rolls, said unit comprising a plate connected to said frame, a flexible finger fixed at one end on said plate to extend across and below the line of travel of the slivers, and a contact on said plate at the opposite free end of said finger whereby a broken sliver falling upon the finger will move this free end to complete the circuit and stop the machine.
- 10 guide and to lie transversely of the line of travel of said slivers in position to be moved by the weight of a broken sliver falling upon it to affect the circuit and stop the machine.
- 15 5. In an electric stop motion for drawing frames, said frame having sliver supply pack-

ages and draft rolls, an electric circuit, a stop motion in the circuit including a circuit-closing unit located intermediate said supply packages and said draft rolls, said unit comprising a plate connected to said frame, 20 a flexible finger fixed at one end on said plate to extend across and below the line of travel of the slivers, and a contact on said plate at the opposite free end of said finger whereby a broken sliver falling upon the finger will 25 move this free end to complete the circuit and stop the machine.

In testimony whereof I affix my signature.

WALTER J. SCOTT.
